CLAIM

The ornamental design for a holder for mobile telephones, as shown and described.

DESCRIPTION

FIG. 1 is a perspective view of a holder for mobile telephones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the holder for mobile telephones where the holder for mobile telephones is in a first configuration of use;

FIG. 10 is a perspective view of the holder for mobile telephones where the holder for mobile telephones is in a second configuration of use;

FIG. 11 is a perspective view of the holder for mobile telephones where the holder for mobile telephones is in a third configuration of use; and,

FIG. 12 is an exploded perspective view of the holder for mobile telephones.

The broken lines in the drawings depict portions of the holder for mobile telephones that form no part of the claimed design.
